UNITED STATES PATENT OFFICE.

ARTHUR B. WEBB, OF WATERTOWN, WISCONSIN, ASSIGNOR TO MONARCH TRACTORS,
INCORPORATED, OF WATERTOWN, WISCONSIN, A CORPORATION OF DELAWARE.

ROAD PLOW.

Application filed December 3, 1924. Serial No. 753,710.

To all whom it may concern:

Be it known that I, ARTHUR B. WEBB, a citizen of the United States, residing at Watertown, in the county of Jefferson and the State of Wisconsin, have invented a certain new and useful Improvement in Road Plows, of which the following is a full, clear, concise, and exact description.

My invention relates to road plows and is of particular use in plows which are employed to remove snow.

Runners or other bearers for plows now in use may ride up on hard snow and hold the plow shovels in position to prevent them from materially removing the snow unless these shovels have compensating downward adjustment. A downward adjustment of the shovel of such a plow that is sufficient to accommodate the runners may also effect too great removal of the snow, particularly upon crowned roads, it being desirable to leave some snow for sleighs and other vehicles.

In carrying out my invention, I employ one or more supplemental shovels in connection with the main shovel of a plow, each tracking with a trailing plow supporting runner or other bearer and arranged to have its cutting edge below the cutting edge of the main shovel to clear the paths for the trailing runners. In the case of light snow, the runners may find their desired level without the assistance of supplemental shovels, wherefore I preferably make these supplemental shovels so adjustable that their cutting edges may be coincident with or above the level of the cutting edge of the main shovel. This adjustment is also of service in determining the depths of the cuts that are to accommodate said runners. The main and supplemental shovels are desirably assembled directly together, means being preferably employed for tilting the main shovel together with the supplemental shovels.

My invention also resides in means whereby the main shovel, together with the supplemental shovels, if such be employed, may be tilted upwardly at the front of the plow, there being a carrying bearer or roller supporting the shovels when lifted, whereby the plow may travel with the shovels removed a wide distance from the roadway, either during mere transportation or to escape large obstructions.

The invention will be more fully explained in connection with the accompanying drawings in which Fig. 1 is a side elevation of a plow as I preferably construct it, together with a vehicle in pushing relation to the plow; Fig. 2 is a sectional plan view on line 2—2 of Fig. 1; Fig. 3 is a sectional view on line 3—3 of Fig. 2; Fig. 4 is a front view of the plow; Fig. 5 is a rear elevation of the plow, on line 5—5 of Fig. 1; Fig. 6 is a sectional view on line 6—6 of Fig. 2; Fig. 7 is a sectional view on line 7—7 of Fig. 5; Fig. 8 is a sectional view on line 8—8 of Fig. 6; Fig. 9 is a view of a part of the structure as it appears in Fig. 70, on a larger scale.

The main shovel 1 is forwardly and downwardly inclined, as usual, being mounted upon the front sloping members 2 of the triangular frame whose horizontal base members 3 run close to the ground and whose upright side members 4 are in the rear of the plow. As illustrated, an upright wall 5, extending longitudinally of the plow, is disposed at the middle of said shovel and above the same and is connected by diverging curved plates 6 at the rear of the plow with the upright transverse wall 7 that is supported by the frame members 4 and which extends from the rear of the shovel, a sufficient distance above the same to prevent the snow from being thrown materially upon the tractor 8 or other pushing vehicle that is in the rear of the plow. Dischargers 9 are disposed above the plow immediately in front of the wall 7 and are turned in a vertical plane which is transverse to the plow. As illustrated, these dischargers are inclusive of blades mounted upon shafts 10 extending longitudinally of the plow and driven by sprocket chains 11, these chains in turn being driven by sprocket wheels 12 that are driven by an internal combustion engine 13 or other suitable means. Adjustable deflectors 9' serve to define the extent to which the dischargers laterally discharge snow being removed by the plow.

In operation, the plow is borne upon bearers that are preferably in the form of rollers 14, 15 and 16, and other bearers that are in the form of runners 17, 18 and 17', 18'. The roller or bearer 14 is in the rear of the plow midway between its sides, the bearings 19 for the roller being carried at

the bottom of the frame 20. This bearer 14 is spaced apart longitudinally of the plow from the bearers 15, 16, 17 and 18, these latter bearers being also at the sides 5 of the plow whereby the aforesaid frame work is given what may be termed a three-point support when the plow is in operation. The runners 17', 18' are also desirably at the sides of the plow. The location of the 10 engine and the other parts is such that the greater part of the weight of the plow is carried upon the long rear roller 14 and the runners 17', 18' so that the plow will not tend to turn upon the common axis of the 15 rollers 15, 16 in a direction to lift the rear of the plow upwardly but will tend to lower the rear of the plow and elevate the cutting edge of the shovel.

The plow has other characteristics which 20 will later be described, it being now in order to show the relation between the plow and the vehicle that effects its propulsion.

The vehicle illustrated is in the form of a tractor employing endless chain tracks 23 which are suitably propelled by means of an engine provided upon the tractor and controlled by an engineer stationed within the cab 24, as is familiar to those skilled in the art. Each endless track passes about the 25 wheels 25 and 26 at the ends of its orbit and there is a frame 27 surrounded by each track which is carried upon the shafts 28, 29 of the wheels 25, 26 and which frame is further supported by the rollers 30 upon the 30 bottom stretch of the surrounding track. The two frames 27 swing independently upon a transverse shaft 31 which depends from a horizontal frame 32 that carries the cab 24 whereby each endless track of the 35 tractor is capable of oscillating in an upright plane with respect to the other, in accordance with the common practice. The frame work of the tractor which carries the transverse shaft 31 has a forward trans- 40 verse member 33. Brackets 34, 35 are secured to the frame member 33 and project rearwardly therefrom. These brackets are integrally cast with a spring barrel 36 having a reduced rear end 37. A rod 38 extends 45 along the axis of the spring barrel to be surrounded by the coiled spring 39 abutting against the rear end wall of the barrel and pressing forwardly upon the head 40 provided upon the front end of said rod. The 50 rear end of this rod is in hinged connection with the forward end of the bar 41, the rear end of this bar passing through the horizontal opening 42 at the middle of an axle 43 at the rear of the tractor. The rear 55 end of the bar 41 is in hinged connection with the apex of the triangular frame 44, the assembly of this bar and frame being desirably effected by a bolt 45 passing through a block 46 which is bolted to and 60 within the apex portion of the frame 44.

The base of the triangular frame 44 is bolted to the transverse bar which is at the rear of the tractor and is connected with the rear ends of the longitudinally disposed horizontal push bars 48 whose forward ends 70 are pivotally connected with the brackets 49 which are assembled with the base members 3 of the frame that carry the shovel 1. As the tractor is propelled, it pushes the plow because of the pulling action exerted 75 by the frame member 33 upon the spring barrel 36. The rear end of this barrel pushes upon the rear end of the spring, the forward end of the spring pushes forwardly upon the rod enlargement 40 of the rod 38 and 80 this rod pulls upon the bar 41, which, in turn, pulls upon the member 47. The latter member pushes upon the rear ends of the bars 48 whose forward ends push upon the brackets 49 to push the plow. The forward 85 ends of the push bars 48 are bifurcated to embrace the rear upright corner members 4 of the shovel carrying frame, these members being rectangular to prevent the material turning movement in a horizontal plane of 90 the push bars and plow, whereby the tractor and the plow being pushed by the tractor are maintained in fixed alignment in the line of travel. The brackets 49 are pivotally assembled between the forward portions of 95 the bifurcated front ends of the push bars.

The level of the cutting edge 50 of the shovel is adjusted by swinging the shovel upon the common transverse axis of the rollers 15 and 16. In order to effect this 100 adjustment of the shovel, I provide means permitting the tilting of the frame upon these rollers with respect to the rear rollers 14. This means consists of suitable adjusting mechanism whereby the rear parts 4 of 105 the frame may be raised or lowered while the roller 14 remains upon the roadway. To this end, the frame 20 which is supported upon the roller 14 through the roller bearings 19 is disposed in upright guides 51 that 110 are fixedly assembled with the shovel supporting frame at the rear of the plow. The frame 20 carries a plurality of power increasing sheaves 52 upon and depending 115 from its top rail. A bridge 53 is assembled with the bottom members 3 of the shovel supporting frame and carries a set of sheaves 54 that are complementary to the sheaves 52. A cable 55 is lashed at one end 56 to the bridge 53 and has its other end 120 lashed to the winding drum 57 which is mounted to turn upon the frame member 58 which is assembled with the shovel supporting frame. The cable is weaved back 125 and forth between the two sets of pulleys so that when the drum is turned the bridge 53 and the guideways 51, together with the rear of the shovel supporting frame will either be elevated or allowed to be lowered 130 by the weight upon the shovel according to 135

the direction of rotation of the drum whereby the shovel cutting edge 50 may be correspondingly lowered or raised.

The mechanism for turning the drum is governed by the operator in the cab 24 who is provided with an operating wheel 58 for this purpose, the shaft of this wheel being coupled by means of a universal joint 59 with one end of a shaft 60 formed in telescopically coupled sections, the forward end of the shaft being coupled by another universal joint 61 with a worm 62 meshing with a worm wheel 63 which is fixed upon the shaft 64 that carries the drum 57.

The extent to which the cutting edge of the shovel may be lowered is limited by the engagement of the rear parts 3' of the shovel supporting frame, with the forward end portions of the push bars. Further raising of the rear of the shovel supporting frame will raise all of the plow structure except the rear roller 14, the entire plow structure then moving upon the fulcrum axis furnished by the rocking engagement of the push bar structure with the axle 43. The rollers 15 and 16 and the four runners are raised from engagement with the roadway when the rear of the plow frame is sufficiently lifted by the action of the winding drum 57, whereby these bearings are relieved from wearing contact with the roadways when the plow is being transported thereover, this being particularly advantageous when the roadways are substantially free of snow. The rollers 15 and 16 desirably extend downwardly through the runners 17 and 18, each of these runners that is penetrated by a roller being, in effect, a double runner with one runner upon each side of the corresponding roller. The rollers 15 and 16 may support the forward part of the plow when it is not desired to elevate the portion of the plow in front of the rear rollers 14, the rollers 15, 16 then serving to maintain the front runners sufficiently clear of the roadway to prevent hard wear thereupon when the plow is being transported over bare roads. The rear runners may be correspondingly elevated out of wearing contact with the roadways when the rear of the plow is sufficiently raised by the cable 55.

The runners on each side of the plow track with each other and find their way to a suitable level in soft snow to enable the properly adjusted shovel to clean off the snow to the extent determined by the adjustment of the shovel. Where the snow is so hard that the runners would ride up on it and thereby prevent the cutting edge of the shovel from reaching the snow, I provide supplemental shovels 64 which track with the runners and the rollers 15 and 16, the supplemental shovels being adjusted to have their cutting edges below the cutting edge

of the main shovel to form pathways for the trailing runners and rollers that are sufficiently deep to enable the cutting edge of the main shovel to reach the snow and enter the same to the depth determined by the adjustment of the main shovel. These supplemental shovels are desirably in hinged connection at 65 with the frame work carrying the main shovel, the supplemental shovels having wings 66 penetrated by the stems of removable bolts 67, these bolts being receivable in various holes 68 that are located at different heights through the extension 68' of the shovel supporting frame, whereby the heights of the cutting edges of the supplemental shovels may be regulated, both with respect to the roadway and with respect to the cutting edge of the main shovel, the range of the adjustment of the supplemental shovels being such that not only may pathways be cut sufficiently deep for the rollers and runners at the sides of the plow but that the cutting edges of the supplemental runners may be elevated above the cutting edge of the main shovel so that the main shovel may operate alone. When the plow is in use upon snow, which is not sufficiently hard to prevent the runners and side rollers from entering the same to a sufficient depth, the supplementary shovels are desirably placed out of service by adjusting them with respect to the main shovel, but the invention is not to be limited to this adjustability, since it is within the scope of my invention to provide a fixed relation between the supplemental shovels and the main shovel with the cutting edges of the supplemental shovels so related to the cutting edge of the main shovel that when the rear of the plow is raised, the supplemental shovels will have their cutting edges lowered to the desired extent with respect to the cutting edge of the main shovel.

Many of the objects and advantages arising from the plow of my invention have been fully set forth and will, with others, not specifically dwelt upon, be fully realized by those skilled in the art.

Changes may be made without departing from my invention.

Having thus described my invention, I claim:

1. A road plow including a main shovel; rollers at the sides of the shovel and another between the sides of the plow, these rollers being in supporting relation to the shovel; runners upon the sides of the shovel downwardly through which the first aforesaid rollers project; and supplemental shovels ahead of and tracking with said runners and the rollers projecting therethrough and adjustable to shift their cutting edges downwardly and below the cutting edge of the main shovel.

2. A road plow including a main shovel;

- rollers at the sides of the shovel and another between the sides of the plow; these rollers being in supporting relation to the shovel; and supplemental shovels ahead of and tracking with the first aforesaid rollers and adjustable with respect to the main shovel to shift their cutting edges downwardly and below the cutting edge of the main shovel.
- 10 3. A road plow including a main shovel; bearers at the sides of the shovel and another between the sides of the plow, these bearers being in supporting relation to the shovel; and supplemental shovels ahead of and tracking with the first aforesaid bearers and adjustable with respect to the main shovel to shift their cutting edges downwardly and below the cutting edge of the main shovel.
- 20 4. A road plow including a main shovel; a bearer in supporting relation to said shovel; and a supplemental shovel ahead of and tracking with said bearer and adjustable to shift its cutting edge downwardly and below the cutting edge of the main shovel.
- 25 5. A road plow including a main shovel; a bearer in supporting relation to said shovel; and a supplemental shovel ahead of and tracking with said bearer and arranged to have its cutting edge below the cutting edge of the main shovel.
- 30 6. A road plow including a main shovel; a bearer in supporting relation to said shovel; a supplemental shovel ahead of and tracking with said bearer and adjustable relatively to the main shovel to shift its cutting edge downwardly and below the cutting edge of the main shovel; and mechanism for tilting the main shovel and the supplemental shovel with it.
- 35 7. A road plow including a main shovel; a bearer in supporting relation to said shovel; a supplemental shovel ahead of and tracking with said bearer and arranged to
- have its cutting edge below the cutting edge of the main shovel; and mechanism for tilting the main shovel and the supplemental shovel with it.
- 40 8. A road plow including a tiltable shovel; forward bearers upon which the shovel may be turned; a rear bearer in supporting relation to the shovel; and mechanism for moving the rear of the shovel up and down with respect to the rear bearer and thereby turning the shovel upon the forward bearer, in combination with a vehicle in pushing relation to the plow; push bars mounted to swing at their rear ends upon said vehicle and in pushing relation to the plow at their forward ends and engageable by the plow when lifted to a predetermined extent with respect to its rear bearer, the plow in being further elevated then swinging upwardly with the push bars and together with the forward bearers while the rear bearer remains upon the roadway.
- 45 9. A road plow including a tiltable shovel; forward bearers upon which the shovel may be turned; a rear bearer in the form of a roller in supporting relation to the shovel; and mechanism for moving the rear of the shovel up and down with respect to the rear bearer and thereby turning the shovel upon the forward bearer, in combination with a vehicle in pushing relation to the plow; push bars mounted to swing at their rear ends upon said vehicle and in pushing relation to the plow at their forward ends and engageable by the plow when lifted to a predetermined extent with respect to its rear bearer, the plow in being further elevated then swinging upwardly with the push bars and together with the forward bearers while the rear bearer remains upon the roadway.

In witness whereof, I hereunto subscribe my name.

ARTHUR B. WEBB.
